UNITED STATES PATENT OFFICE.

ANTON HORVAT, OF BALTIMORE, MARYLAND.

DESIGN FOR WEDDING RING.

Application filed October 28, 1926. Serial No. 19,510. Term of patent 14 years.

To all whom it may concern:

Be it known that I, ANTON HORVAT, a citizen of the United States, residing at Baltimore, in the county of Baltimore and State of Maryland, have invented a new, original, and ornamental Design for Wedding Rings, of which the following is a specification, reference being had to the accompanying drawings, forming part thereof.

Figure 1 is a perspective view of the ring.

Figure 2 is a detail view of the ring as seen from the inner edge showing the contour.

I claim:

The ornamental design for wedding ring, as shown.

ANTON HORVAT.
